UNITED STATES PATENT OFFICE.

LEWIS FERRY MOODY, OF PHILADELPHIA, PENNSYLVANIA.

IMPULSE TURBINE.

Application filed May 23, 1923. Serial No. 640,826.

To all whom it may concern:

Be it known that I, LEWIS FERRY MOODY, a citizen of the United States, residing at Philadelphia, in the county of Philadelphia and State of Pennsylvania, have invented certain new and useful Improvements in Impulse Turbines, of which the following is a specification.

This invention relates to hydraulic turbines and particularly to turbines of the impulse type. The object of the invention is to provide a turbine in which the jet will be annular in form so as to continuously impinge against all of the wheel buckets and in which the jet will be directed diagonally inward so as to prevent diffusion of the stream lines and to maintain the jet as a solid stream until it enters the runner.

A further object of the invention is to provide an impulse turbine in which the flow through the buckets will be spread and decelerated so as to be discharged with small velocity and correspondingly small loss of energy.

In the accompanying drawings illustrating the invention

Fig. 1 is a vertical sectional view of one embodiment in a vertical shaft turbine.

Fig. 2 is a similar view of a modification, Figs. 3 and 4 are sections of the runner on lines 3—3 and 4—4 respectively of Fig. 2.

Fig. 5 is a vertical sectional view of a turbine showing a further modification, and

Figs. 6 and 7 are sectional views of the runner on lines 6—6 and 7—7 of Fig. 5.

In the embodiment of the invention shown in Fig. 1 the flow entering through intake 5 is directed through orifice 6, the stay vanes 7 in advance of the orifice having their surfaces inclined to the radial to impart to the flow where it leaves the orifice an inclination with respect to a plane containing the turbine axis. The lower edge of orifice 6 is formed by the renewable, stationary ring 8 and the upper edge of the orifice is the end 9 of the vertically movable annular plunger 10 adjusted, for instance, by fluid pressure above or below the piston portion 11. These edges are so arranged that the jet J from them is directed diagonally downward and inward around a complete circle against the buckets 12 of runner 13 on shaft 14. The jet J is spaced away from both the crown 16 and shroud ring 17 of the runner, and the runner vanes may either be made of simple form with substantially

straight elements transverse to the flow or the bucket surface may be given curvature in both directions, as shown in Figs. 2—4. The shroud ring 17 has no hydraulic function, and may be omitted if desired. When used it will assist in supporting the vanes against centrifugal force, and will tend to reduce the windage of the vane tips. As shown, the turbine is arranged with a draft tube O below it and passages 19, 20 are shown for admitting air both above and below the jet J in order to insure that the jet will remain free and not fill the passages. These air inlets may be provided with regulating valves as desired. A passage may be left below the casing for inspecting or removing the runner.

An efficient form of jet can be produced at all degrees of opening of the plunger 10, the jet being clear of all guiding surfaces which would tend to create friction from the time it reaches its full discharge velocity until it enters the runner, and the distance between the discharge orifice of the nozzle and the entrance to the runner is small so that the air friction of the high velocity jet is reduced to a minimum. The inwardly directed arrangement of the jet J prevents a tendency for the jet to increase in cross sectional area normal to the lines of flow, and thus prevents diffusion and insures that the jet will continue as a solid stream until it enters the runner. The diagonal direction makes it possible for the water to flow from the nozzle to the runner discharge without unnecessary deflection and in smooth curves, and counteracts the tendency of the flow to be turned wholly into the radial outward direction at the exit from the runner. The diagonal jet thus gives better distribution of the flow and avoids a concentration of the flow at the portion of the runner where high relative velocity is required between the water and the vane surfaces. The diagonal direction of the jet at entrance is advantageous because it thus tends to keep the flow as near the axis as possible while at the same time permitting a sufficient lateral spreading of the flow to provide a low discharge velocity from the runner.

The lateral spreading out and deceleration of the flow through the buckets is provided for in the turbine of this invention and is desirable for efficient action. When the water leaves the buckets it should have a low discharge velocity, since otherwise

there will be an undue loss of energy in the velocity head of the water leaving the runner. The flow should, therefore, spread out laterally as shown so that the width of the flow at discharge will be much greater than that at entrance in order to provide the necessary area of discharge. This characteristic is present in all of the turbines shown in the drawings.

10 In the modification shown in Fig. 2 the lower edge 8' of the orifice 6' is made adjustable by annular plunger 10' operated, for instance, by fluid pressure above or below piston 11' so as to vary the thickness 15 of the jet by raising or lowering its lower surface.

In this embodiment the buckets 30 are doubly curved or cup shaped, the surface of each bucket curving into and merging with 20 the conical crown or hub 31 of the runner 32. Since the upper surface of the jet J' remains in the same position for all gate openings, the water can remain in contact with the crown 31 at all gate openings.

25 Sections of the wheel buckets 30 are shown in Figs. 3 and 4, section 3—3 being taken substantially in the direction of flow and section 4—4 transverse to the flow at the hub 31 and in the direction of flow at the discharge. In this arrangement also a continuous draft tube could be provided if desired, the draft tube section immediately below the runner not, however, being shown in the figure. Access of air would be provided both 35 above and below the jet, as in Fig. 1, the air passage 19' above the jet being shown and means of control being indicated by the valve 39 on the turbine casing. A renewable nozzle piece 37 at the upper lip of the 40 nozzle is shown in this figure. The buckets 30 may be separately formed and bolted to the hub 31 if desired. The cup shape of the buckets cooperates with the diagonal inward direction of the jet J' to turn the jet 45 into the proper direction of discharge, to control the amount of lateral spreading and to provide efficient lines of flow.

In the embodiment of the invention shown in Figs. 5, 6 and 7 flow entering through the 50 intake 35 is directed through the orifice 36, the vanes 37 and 37' in advance of the orifice having their surfaces inclined to the radial to impart to the flow where it leaves the orifice an inclination with respect to a plane 55 containing the turbine axis. In this modification the vanes 37' adjacent the orifice 36 are movably carried by the adjustable ring member 38 forming the lower edge or lip of the orifice 36, this ring member being 60 moved by fluid pressure, admitted through pipes 39 and 40 to opposite sides of the annular piston member 41. The buckets 50 of the runner have an extended discharge area for the jet, that is a large area trans- 65 verse to the flow lines at the discharge from

the buckets so that the flow in passing through them is free to spread or widen out laterally and have a relatively small discharge velocity when it leaves the buckets. The jet from the orifice 36 is directed diagonally 70 downward and inward around a complete circle against the buckets 50 which are curved or cup shaped with a surface of each bucket curving into and merging with the conical crown or hub 51 of the runner. Sections of the wheel buckets 50 are shown in Figs. 6 and 7, section 6—6 being taken along a conical surface having elements indicated by the line 6—6 of Fig. 5 and section 7—7 being taken along a conical surface having 75 an element indicated by the line 7—7 of Fig. 5, each of said conical surfaces having its axis coinciding with the axis of the turbine. Air is supplied to the interior of the jet through the valve means 54 and openings as indicated at 55 just above the runner hub. Similar valve means will be provided to control the admission of air to the outer surface of the jet so that a desired 80 vacuum may be maintained in the jet chamber by adjustment of these valve controls, it being understood that such control of the air supply is applicable to all of the turbines shown. The jet chamber in each of the figures may be similarly arranged to contain a vacuum and to act as a draft tube, being laterally enclosed and discharging below the tailwater surface. The air supply valves may either be adjusted by hand or 85 provided with automatic control by such means as a float or an element regulated by the pressure in the draft tube; so that only enough air may be admitted to prevent the tailwater being drawn up to a level unduly 90 near the runner, but still to preserve a high vacuum within the tube. By maintaining such a vacuum a large part of the static head between the runner and tailrace may be utilized. In other features the turbine 95 of Fig. 5 also corresponds in a general way 100 to the turbines shown in Figs. 1 and 2.

In the turbine of this invention in order to obtain a very high specific speed the angle between the direction of the jet and the direction of motion of the wheel buckets at the point where the jet enters them may be made relatively large, for example, greater than 45°, and the wheel bucket may be given a forward inclination in the direction of motion of the runner in order to permit a high linear velocity of the wheel buckets to be employed. In order to obtain high efficiency, the discharge area of the runner will in general be made more than double the transverse area of the jet at the nozzle and in most cases more than three or four times the jet area.

While the invention has been illustrated in connection with specific embodiments in vertical shaft turbines it is not confined to 130

the arrangements shown but is intended to cover such modifications thereof as are within the scope of the appended claims.

I claim:

5. 1. In an impulse turbine the combination with means for forming an annular jet and directing it diagonally inward, of a runner receiving said jet.
10. 2. In an impulse turbine the combination with means for forming an annular jet and directing it diagonally inward, of a runner receiving said jet and having central hub surfaces inclined in the direction of the jet.
15. 3. In an impulse turbine the combination with means for forming an annular jet and directing it diagonally inward, of a runner receiving said jet and having buckets extending transversely across the jet.
20. 4. In an impulse turbine the combination with means for forming an annular jet and directing it diagonally inward, of a runner receiving said jet, and means for relatively adjusting opposite edges of said jet forming means to vary the thickness of the jet.
25. 5. In an impulse turbine the combination with means for forming an annular jet and directing it diagonally inward, of a runner receiving said jet, and means to impart a whirl to said jet before entering said runner.
30. 6. In an impulse turbine the combination with means for forming an annular diagonally inward directed jet, of a runner receiving said jet and comprising a hub portion and buckets carried thereby inclined to extend transversely across the jet.
35. 7. In an impulse turbine the combination with means for forming an annular diagonally inward directed jet contracting after discharge from the orifice edges of said forming means, of a runner receiving said jet and comprising a hub portion and buckets carried thereby inclined to extend transversely across the jet.
40. 8. In an impulse turbine the combination with means for forming an annular jet and directing it diagonally inward, of a runner
45. 9. In an impulse turbine the combination with means for forming an annular jet and directing it diagonally inward, of a runner receiving said jet, and separate air inlet means inside and outside of said jet.
50. 10. In an impulse turbine the combination with means for forming an annular jet, of a runner receiving said jet and having cup shaped buckets adapted to guide the stream lines as a compact mass.
55. 11. In an impulse turbine the combination with means for forming an annular jet, of a runner receiving said jet, the discharge area of said runner being substantially greater than twice the transverse area of said jet at the nozzle.
60. 12. In an impulse turbine the combination with means for forming an annular jet, of a laterally enclosed chamber into which said jet is directed, said chamber discharging below the level of the tailrace and a runner within said chamber receiving said jet.
65. 13. In an impulse turbine the combination with means for forming an annular jet, of a laterally enclosed chamber into which said jet is directed, said chamber discharging below the level of the tailrace and a runner within said chamber receiving said jet and means for admitting air to said chamber.
70. 14. In an impulse turbine the combination with means for forming an annular jet, of a runner receiving said jet and guiding means to impart tangential components to said jet before it enters said runner, said guiding means being axially adjustable.
75. 15. In an impulse turbine the combination with means for forming an annular jet and directing it diagonally inward, of a runner receiving said jet and means for adjusting one edge of said jet forming means to vary the thickness of the jet.

LEWIS FERRY MOODY.
